UNITED STATES PATENT OFFICE.

LEO SCHLESINGER, OF NEW YORK, N. Y.

DESIGN FOR A HORN.

42,650.

Specification for Design.

Patented June 18, 1912.

Application filed April 1, 1912. Serial No. 687,859. Term of patent 3½ years.

To all whom it may concern:

Be it known that I, LEO SCHLESINGER, a citizen of the United States, and a resident of the city, county, and State of New York, have invented a new, original, and ornamental Design for Horns, of which the following is a specification, reference being had to the accompanying drawing, forming part thereof, in which—

Figure 1, is an elevation of a horn show-

ing my new design, and Fig. 2, is an edge view thereof.

I claim:

The ornamental design for a horn, as shown.

LEO SCHLESINGER.
